CLAIM

The ornamental design for an electrical plug socket switch, substantially as shown and described.

DESCRIPTION

FIG. 1 is a top, front and right side perspective view of an electrical plug socket switch, showing our new design;

FIG. 2 is a front elevational view thereof;

FIG. 3 is a rear elevational view thereof;

FIG. 4 is a top plan view thereof, the bottom view being identical; and,

FIG. 5 is a right side elevational view thereof, the opposite side being a mirror image.
